(57) **CLAIM**

The ornamental design for a motorcycle timing cover, as shown and described.

DESCRIPTION

FIG. 1 is a front perspective view of the motorcycle timing cover of the present invention.

FIG. 2 is a front elevation view thereof.

FIG. 3 is a rear elevation view thereof.

FIG. 4 is a top view thereof.

FIG. 5. is a bottom view thereof; and,

FIG. 6 is a right side view thereof, the left side being a mirror image of the right side.

The rear surface, front surface portions and lower protrusion of the motorcycle timing cover shown in broken lines form no part of the claimed design.
